LOOSE-LEAF BINDER

James Cooper, Solvay, and John M. Wall, Syracuse, N. Y., assignors to Hall & McChesney, Inc., Syracuse, N. Y., a corporation of New York

Application November 13, 1936, Serial No. 110,716

13 Claims. (Cl. 129—23)

This invention relates to a loose leaf binder of the type embodying a back member, a cover hinged to the back member, a plurality of leaf impaling posts, the back member being detachably secured to the ends of the posts and, when detached from like ends of the posts, is movable away from the posts, to permit insertion and removal of the leaves in the binder.

The binder herein referred to is of the type employed generally in public offices, and in which public records, such as deeds, mortgages etc., are recorded. It is accordingly necessary to detach the back member from the posts to permit insertion of new pages each time an instrument is recorded.

Heretofore, after the posts have been detached from the back member and the additional sheets inserted, it has been necessary to manually move the back member toward the posts into post engaging position, and then close the cover. The closing of the cover, after the back member has been moved into post engaging position, may, per se, effect securement of the back member to the post. However, movement of the cover toward closed position, when the back member is swung out away from the posts and the leaves, produces no useful result inasmuch as the cover simply moves about its pivoted connection to the back member.

The general object of this invention is a binder of the type referred to, embodying structure which is operable to automatically effect movement of the back member into post engaging position during closing of the cover. That is, after one side of the back member has been detached from like ends of the leaf impaling posts and swung outwardly, it is not necessary to manipulate the back member into post engaging position, but this movement is accomplished automatically by simply closing the cover of the binder in the ordinary normal manner.

The invention consists in the novel features and in the combinations and constructions hereinafter set forth and claimed.

In describing this invention, reference is had to the accompanying drawings in which like characters designate corresponding parts in all the views.

Figure 1 is a plan view, partly in section, of the binder with both covers lying in flat open position, and with one side of the back member detached from the ends of the posts.

Figure 2 is a transverse, sectional view, with parts in elevation, taken through the back member and contiguous portions of the covers, with one of the covers arranged in vertical open posi-

tion and one side of the back member detached from the leaf posts.

Figure 3 is a view similar to Figure 2, with the back member swung outwardly from the post and leaves.

Figure 4 is a perspective view of one of the post securing housings and a contiguous portion of the back member and adjacent cover.

The binder embodies a rigid back member comprising, in this instance, a plate 10, each longitudinal edge of which is formed with a plurality of spaced apart hinge members 11. An outer back 12 is secured in spaced apart relation to the plate 10 by means of a plurality of spaced apart braces 13 extending transversely of the outer back 12 and 15 being secured thereto. The ends of the braces 13 terminate in hinge eyes 14. The outer back 12 is finished with a suitable outer finishing layer 15.

The covers here shown are of usual laminated construction consisting of inner and outer layers 20 16, 17, between which is secured a metallic strip or plate 18 which projects beyond the inner edge of the cover and which is also formed with a plurality of spaced apart hinges 19. The hinges 11 and 19 are arranged coaxially and are pivotally connected on rod 20, whereby the covers are movable on the pivot rods 20 into open and closed positions. The outer surface of the cover is also provided with a suitable finishing layer 21 which preferably extends between the hinged joint described 30 and the outer back member 12, as at 22.

A plurality of leaf impaling posts 25 are arranged in spaced apart relationship and extend transversely of the plate 10. The back member is provided with means for detachably securing the 35 ends of the posts to the back member with the posts arranged in spaced apart relationship to the plate 10.

As here shown, this means comprises a tubular housing 26 rectangular in cross section and being 40 provided along one longitudinal edge with a plurality of spaced apart hinged members 27. The hinge members 11, 14, 19 and 27 are arranged coaxially on the pivot rod 20 forming a piano hinge between the back member, the covers, and the 45 housings 26, whereby the covers are movable on the pivot rod 20 into open and closed position, and the housings 26 swing about the pivot rods 20 into and out of post engaging position.

The inner and outer sides of the housings 26 are 50 provided with apertures 30 arranged so as to receive the ends of the posts 25. A latch bar 31 is slidably mounted in each housing 26 and is provided with cut out portions 32 adjacent each of the openings 30 in the housings. The cutouts or 55

apertures 32 in bars 31 are arranged in pairs and separated by a transversely extending partition 33. The latch bar 31 extends outwardly through one end of the housing and is provided with a finger piece 35. A spring 36 is inserted between the inner end of the latch bar 31 and the adjacent end of the housing and yieldingly moves the latch bar toward the open end of the housing. The ends of the posts are formed with notches to receive the partition 33. One side wall 37 of the notch is formed straight, and the opposite wall is formed with an angular cam surface 38 adjacent the outer end of the posts, which terminates in a ledge 39.

15 When the housings 26 are moved about the pivot rods 20 toward the ends of the post 25, the partition 33 engages the cam surface 38 causing the bar to move inwardly against the pressure of spring 36. After the partition 33 passes under 20 the ledge 39, spring 36 urges the bar 31 toward the open end of the housing, moving the partition 33 under the ledge 39 and thus detachably securing the housing 26 to the ends of the posts 25, as illustrated at the upper left of Figure 1. 25 Preferably, a housing 26 is secured along each longitudinal side of the plate 10, in order that the posts 25 may be detached at either end to permit insertion and removal of the leaves from either the front or the back of the binder.

30 It will be observed, as the description proceeds, that the construction and arrangement of the housing 26, or their equivalent, may be considerably modified without departing materially from the scope of this invention. For example, 35 the housings may be rigidly secured to the back member, or the back member be secured to the ends of the posts 25 by means equivalent to the housings and latch bar 31.

When it is desired to remove or insert additional leaves in the binder, one of the covers is 40 moved to open position, and the latch bar 31 is pressed inwardly by finger piece 35, moving the partition members 33 from beneath the ledges 39, permitting the housing 26 to swing outwardly 45 from engagement with the ends of the posts 25. The entire back member is then swung outwardly from the posts and the leaves about the pivot 20 at the opposite side of plate 10, as illustrated in 50 Figure 3. The leaves are illustrated by dotted outline in Figures 2 and 3. When the operation of removing or inserting the leaves is completed, the back member is moved into vertical position, Figure 2 and the detached housing 26 is moved 55 into vertical position, Figure 2, and the detached housing 26 is then moved about the pivot 20 into engagement with the ends of the posts.

This invention has to do particularly with the structure for effecting movement of the back member into post engaging position, and comprises means carried by the back member and cooperable with the cover for automatically effecting movement of the back member upon closing movement of the cover.

As here shown, this means comprises a pair of links 40, 41 for each cover. One end of the link 41 is pivoted to the housing 26, as at 42, or rather to a projection 43 secured to the inner side of the housing. The opposite end of the link 41 is pivoted to one end of the link 40, as at 44, 70 and the opposite end of this link 40 is pivoted to a bracket 45 secured centrally of the back plate 10. A chain or cord 46 is secured to the outer end of each of the inner links 40 and passes around a pulley 47 journaled on a shaft 48 extending 75 transversely beneath the back plate 10. The

opposite end of the chain 46 is connected to a tension spring 49 secured to the back plate, as at 50. The spring 49, through chain 46, yieldingly moves the outer end of the link 40 toward the back plate 10 and accordingly, tends to rotate 5 the housing 26 outwardly against the cover or cover plate 18. When the housing is secured to the end of the posts, the links 40, 41, assume an angular relationship as shown by the links associated with the bottom housing in Figure 2. 10 When the housing 26 is detached from the ends of the posts, as previously described, and the housing permitted to rotate outwardly about the pivot 20 with the cover in open position, the links 40, 41, assume the position shown in Figure 2. 15 The inner end of the link 41 is provided with a stop 52 which coacts with the link 40 intermediate its pivot points and prevents the links or toggle from straightening out. That is, the pivot 42 and the pivot on bracket 45 are arranged to 20 one side of the central pivot 44 when the housing is swung outwardly away from the ends of the posts, see Figures 2 and 3.

When the cover is moved toward closed position, it swings about the pivot 20 until it engages 25 the detached and outwardly swung housing 26. Further closing movement of the cover relative to the back member is prevented inasmuch as the links 40, 41, are maintained in the position shown in Figures 2 and 3 by chain 46 and spring 49. 30 This position and relationship of the links 40, 41 is maintained until the back member is swung to a position substantially parallel with the posts 25, and with the housing 26 in post engaging position. At this time, further pivotal movement 35 of the back member ceases on account of the opposite longitudinal edge of the back plate 10 engaging the opposite housing 26 and further closing movement of the cover is then transferred to the detached housing 26 and tends to rotate 40 the same inwardly about the pivot 20. Due to the relative arrangement and position of the operating parts, this movement of the detached housing 26 about its pivot 20 effects a substantially endwise movement to the outer link 41, 45 causing the toggle to break outwardly from the back plate 10 on the central pivot 44, and the adjacent ends of the levers 40, 41, move outwardly from the back plate 10 until the detached housing 26 is moved into post engaging position. 50 When this position is reached, the slide bar 31 is automatically latched over the ledges 39 of the ends of the posts 25. As previously stated, the binder may be provided with a housing 26 pivoted adjacent each edge and in which there is 55 slidably mounted an identical slide bar 31 and an additional series of links 40, 41 are pivotally connected to the second housing and the back member in the manner above described.

It will be observed that when the links 40, 41, 60 associated with the detached housing, are in substantially straight position, as illustrated in Figures 2 and 3, the associated spring 49 easily maintains the links in this position during pivotal movement of the back about the pivot 20 of 65 the closed cover. During this movement of the back member toward the posts 25, the force exerted against the detached housing 26 by the associated open cover is substantially at right angles to the back plate 10 and accordingly, the 70 toggle formed by the links 40, 41 does not tend to break out during this movement. However, after the back member has been moved into normal vertical position, as indicated in Figure 2, the pivotal movement of the open cover toward 75

closed position imparts a pivotal movement to the detached housing 26 which exerts a force substantially parallel to the back plate 10, whereby the toggle formed by the links 40, 41, is 5 readily broken against the action of the spring 49, and the detached housing permitted to swing about the pivot 20 into engagement with the ends of the posts 25.

It will also be observed that during pivotal 10 movement of the back member toward the posts 25, the spring 49 associated with the links 40, 41, connected to the attached housing, bottom housing Figures 2 and 3, tends to urge the back member toward the posts 25, and as the back 15 member approaches the posts, the angularity of the links 40, 41, associated with the attached housing increases, and when the back member has assumed vertical position, as shown in Figure 2, the force exerted by the spring 49 is 20 sufficient to maintain the back in vertical position and prevent it from swinging outwardly away from the posts and leaves during the remaining closing movement of the cover from the position shown in Figure 2. That is, the 25 action of the second spring 49 is not opposed to the inward pivotal movement of the back member, but rather exerts a force in aid of such movement. Also, the linkage associated with the detached housing operates to maintain the back member in parallel position with respect to the 30 posts 25. It will be observed, Figure 2, that the pivot 44, when the detached housing and associated cover are in parallel relationship to the posts, is located to one side of the opposite cover pivot 20. Accordingly, the force exerted on this 35 linkage by the pivotal movement of the detached housing and cover is in a direction toward the attached housing and away from the back member toward the open edge of the book. With 40 this relative arrangement, the binder may be provided with only one detachable housing and the full automatic closing feature performed by the linkage and spring associated with said housing.

45 The inner edges of the leaves centrally of the back member are notched, or cut away, as at 60, to provide an operating space for the links 40, 41.

The loose leaf binder described is fully automatic in that after it has been manipulated to 50 open position, the back member is reassembled and secured to the ends of the posts simply by closing the open cover in the ordinary manner, and it is not necessary to first manipulate the 55 back member into post engaging position and subsequently close the cover.

It will be observed that the attached housing is held firmly against the inner side of the closed cover by the associated links 40, 41, and spring 60 49, and the posts 25 are maintained in upstanding position and in alinement due to the fact that the ends of the posts extend through the sides of the housings and are firmly secured thereto by latch bar 31.

65 What we claim is:

1. A loose leaf binder including a back member, a cover pivoted along each side of the back member, a plurality of leaf impaling posts extending transversely of the back member and 70 pivotally connected at one end to the back member, said back member being movable about one cover pivot toward and from like ends of said posts, means carried by the back member for detachably securing the back member to said 75 posts upon engagement of said means with the

posts, and means for automatically moving said back member towards said posts and for moving the means carried thereby into engagement with said post ends during closing of the cover adjacent the detached post ends.

2. A loose leaf binder comprising a back member, a cover pivoted along each side of the back member, a housing pivoted along each side of said back member adjacent each cover, a plurality of leaf impaling posts, said housings being 10 movable about their pivots into and out of engagement with said posts, means carried by the housings and operable, upon engagement of the housings with the ends of the posts, to detachably secure the ends of the posts to the housings 15 and being manually operable to release said post ends, said back member being movable about a cover pivot away from the leaves, when the housing adjacent the opposite cover is released from said posts, to permit removal and insertion 20 of the leaves, and a second means, cooperable with the back member and said detached housing, to effect movement of said back member toward the leaves upon closing movement of the cover adjacent the released housing and to permit 25 pivotal movement of the housing by the cover to post engaging position.

3. A loose leaf binder comprising a back member, a cover hinged along each edge of the back member, a plurality of leaf impaling posts extending transversely of the back member between said covers, means for pivotally securing like ends of the posts to the back member adjacent one edge thereof, said back member being provided with means adjacent its opposite edge for detachably securing the opposite ends of said posts to the back member, said back member being movable about said pivot when the opposite ends of the posts are detached from the back member, whereby the detached edge of the back member may be swung outwardly from said posts and leaves to permit insertion and removal of the leaves, means cooperable with the back member and the post securing means on the detached edge of the back member, to effect movement of the back member toward said posts during closing movement of said cover adjacent the detached edge of the back member.

4. A loose leaf binder comprising a back member, a cover pivoted along each edge of the back member, a plurality of posts secured at like ends adjacent one edge of the back member and extending transversely of said member, means mounted on the opposite edge of said back member and operable to detachably secure the opposite ends of the posts to the back member, said back member being movable away from the posts when the same are detached, means tending to urge said back member toward said posts, and means operable, upon closing of the cover adjacent said posts securing means, to move said back member toward the posts.

5. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in opened position, and said back member and detached housing being movable away from said posts to permit removal and insertion of leaves, and means 75

- operable to prevent pivotal movement of the detached housing relative to the back member during initial closing movement of the adjacent cover and to effect movement of the back member toward said posts and to permit subsequent pivotal movement of said detached housing and cover during final closing movement of the cover to bring said housing into engagement with the ends of said posts.
6. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in opened position, and said back member and detached housing being movable away from said posts to permit removal and insertion of leaves, and means cooperable with the back member and detached housing to prevent pivotal movement of the detached housing relative to the back member during initial closing movement of the adjacent cover and to effect movement of the back member toward said posts and to permit subsequent pivotal movement of said detached housing by the cover during final closing movement of the cover to bring said housing into engagement with the ends of said posts.
7. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in opened position, and said back member and detached housing being movable away from said posts to permit removal and insertion of leaves, means operable to prevent pivotal movement of the detached housing relative to the back member during initial closing movement of the cover and to effect movement of the back member toward said posts with the detached housing in post engaging position, and to permit subsequent pivotal movement of said detached housing and cover during final closing movement of the cover to bring said housing into engagement with the ends of said posts, and means cooperable with said back member and the other attached housing for preventing outward movement of the back member from the posts during such pivotal engagement of the detached housing with the ends of said posts.
8. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in opened position, and said back member and detached housing being movable away from said posts to permit removal and insertion of leaves, means yieldingly urging said back member toward said posts, and means operable to prevent pivotal movement of the detached housing relative to the back member during initial closing movement of the cover and to

effect movement of the back member toward said posts and to permit subsequent pivotal movement of said detached housing and cover during final closing movement of the cover to bring said housing into engagement with the ends of said posts. 5

9. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in open position, 10 means yieldingly urging said detached housing against the inner side of said cover, said back member and detached housing being movable away from said posts to permit removal and insertion of the leaves, and means yieldingly urging said back member toward said posts.

10. A loose leaf binder comprising a back member, a cover hinged to each longitudinal edge of the back member, a housing mounted on the pivot of each cover hinge, a plurality of leaf impaling posts extending transversely of the back member and being detachably secured at their ends to said housings, each of said housings, when detached from the posts, being movable about its pivot into engagement with the inner side of the adjacent cover when the same is in open position, 15 means yieldingly urging said detached housing against the inner side of said cover, said back member and detached housing being movable away from said posts to permit removal and insertion of the leaves, and means yieldingly urging said back member toward said posts. 20

11. A loose leaf binder comprising a back mem- 40

ber, a cover pivoted to each side of the back member, a plurality of leaf impaling posts extending transversely of the back member, means carried by the back member adjacent one side thereof and operable upon engagement with the ends 45 of said posts to attach the posts to the back member and being manually operable to detach said posts from the back member, said back member being pivotally secured at its opposite side to the other ends of the posts, said back member being 50 movable away from said posts when detached from the same to permit insertion or removal of the leaves, means cooperable with the cover and said back member, when the same is detached from the posts, for automatically moving the back 55 member toward the posts and the post securing means into engagement with the ends of the posts during closing of the cover adjacent said post attaching means, and said means being operable subsequently to the attachment of the posts and 60 back member to permit free pivotal movement of the cover.

12. A loose leaf binder comprising a back mem- 65

ber, a cover pivoted to each side of the back member, a plurality of leaf impaling posts, means carried by the back member and cooperable with the ends of the posts upon engagement with the same to interlock with the posts, said back member being movable toward and from the posts to 70 permit insertion and removal of the leaves from said posts, and means cooperable with the cover and said back member for automatically moving the back member toward the posts and effecting engagement of said interlock means with the posts during closing of the cover. 75

13. A loose leaf binder comprising a back member, a cover hinged to each side of the back member, a plurality of leaf impaling posts extending transversely of the back member and being pivotally secured thereto at like ends adjacent one side of the same, the opposite side of the back member having means for detachably interlocking with the opposite ends of the posts upon engagement with the same, said last mentioned side of the back member being movable from said

posts when detached therefrom to permit insertion and removal of the leaves, and means cooperable with said back member and the cover adjacent said detached side to automatically move said back member toward the posts and for moving the means carried thereby into engagement with the ends of the posts during closing of said cover. 5

JAMES COOPER.
JOHN M. WALL. 10
